UNITED STATES PATENT OFFICE

FRANK H. NULLMEYER, OF STRUTHERS, OHIO

ROD OR WIRE DRAWING BLOCK

Application filed October 21, 1924. Serial No. 744,895.

The present invention relates to means for drawing rods or wire through reducing means. Ordinarily, the method of drawing rods or wire consists in pointing the rod or wire so that a short end of the same will pass through the reducing die and fastening a puller to this projecting end and pulling a few inches of the rod or wire through the reducing means and then making another grip close to the reducing means, repeating this operation until a sufficient length of the rod or wire has been pulled through the reducing means to reach from the reducing means to the drawing block, where it is fastened to the same with a vise or clamp. This operation consumes considerable time and labor before the block can be set in motion to draw the remainder of the rod or wire through the reducing means.

20 The present invention provides a construction which eliminates this repeated gripping of the pointed end of the rod or wire and takes care of the slack produced in the coil of rod or wire as it winds up on the block. Furthermore, the construction is such that the breakage of rods or wires due to the sudden strain exerted thereon in starting up the block is greatly reduced, thereby increasing the output of rods or wire per block.

30 In the accompanying drawings:—

Figure 1 is a plan view, partly in section, of a preferred form of the invention.

Figure 2 is a transverse vertical section on the line II—II of Figure 1.

35 Figure 3 is a detail sectional view on the line III—III of Figure 1, and

Figure 4 is a perspective view of an element of the construction.

In the illustrated embodiment of the invention the reference numeral 2 designates a reducing die and 3 a rotary drawing block. The drawing block is mounted on a drive shaft 4 and has an annular tapered wall 5 about which a rod or wire is adapted to be wrapped. Journaled on the hub portion 6 of the block and within the annular wall is a sheave 7 having a peripheral groove 8 therein. This sheave is held in position on the hub by a plate washer 9 secured to the hub by bolts 10. A chain 11 is connected at one end to a grip device 12 and at its other end to a bolt 13 which is secured in the sheave and traverses the peripheral groove 8. This chain normally extends through an opening 14 in the annular wall 5. A coil spring 15 lies in a portion of the groove 8 and is fastened at one end to a pin 16 secured in the annular space between the periphery of the sheave and the inner surface of the wall 5. This spring is secured at its other end to the bolt 13. Fas- 55 tened to the upper surface of the sheave by means of a screw 17, and also by means of the bolt 13, is a stop member 18 which projects into the path of a stop member 19 projecting from the inner surface of the annular wall 5. 60 Pivotally mounted upon the upper surface of the sheave is a pawl 20 adapted to engage in a notch 21 in the washer 9.

The operation of the above described construction is as follows: The rod or wire 22 having been pointed to pass through the reducing means 2, the grip device 12 is attached to the pointed end 23 thereof by the operator pulling the grip device and chain 11 through the opening 14 in the wall 5 of the block, thereby rotating the sheave 7 on the hub 6 and elongating the spring 15. This rotation of the sheave is in a direction opposite to the direction in which the block 3 rotates when drawing the rod or wire through 65 the reducing means. The pawl 20 is so located with reference to the notch 21 in the washer 9 that the pawl can be turned into engagement with said notch before the stop 18 engages the stop 19. The parts are then 70 in the position illustrated in Figure 1. It will be apparent that the pawl cooperating with the washer prevents reverse rotation of the sheave by the spring 15. However, when the block 3 is engaged with its driving means and begins to rotate, the initial rotation of the block will cause the spring 15 to be further elongated until the stop 19 engages the stop 18. It will be seen, therefore, that during 75 the initial rotation of the block the pulling force is yieldingly transmitted from the block to the grip device so that the danger of breaking the rod or wire due to sudden strain put upon the rod or wire is greatly reduced. After the stop 19 has engaged the stop 18 80

85

90

95

100

subsequent rotation of the drawing block causes the pulling force to be positively transmitted to the grip device through the chain 11. The pawl 20 will be turned into inoperative position after the stop 19 has come into engagement with the stop 18. After a few turns of the rod or wire have been wrapped on the wall 5 the pulling force will then be transmitted to the grip device through the 10 rod or wire itself and the spring 15 will then function to rotate the sheave on the hub 6 in the same direction that the block is rotating in to draw in the grip device and wrap the chain 11 in the groove 8. This retracting 15 means may be limited by reason of the stop engaging member 18 coming into contact with a second stop member on the block, similar to the stop member 19, but spaced from such member.

20 It will be apparent that the parts required to adapt the present invention to drawing blocks of usual construction are few, very simple and inexpensive. The pawl 20 and notch 21 in the plate 9 will be necessary only 25 on blocks which run very freely on their pivots or shafts, or where the tension of spring 15 is greater than necessary to revolve sheave 7 to take up the slack produced in the rod or wire while being drawn, or where the 30 spring tension would be sufficient to revolve the block 3 in the opposite direction from that in which it runs to draw the rod or wire.

While I have shown and described a preferred embodiment of the invention, it will 35 be understood that the invention is not limited to the exact details of construction shown but may be otherwise embodied within the scope of the appended claims.

I claim:

40 1. The combination with a rotary drawing block having an annular wall on which to wrap a rod or wire and a grip device, of a sheave rotatably mounted within said wall and having a peripheral groove therein, a 45 relatively unyielding element connected at one end to said grip device and at its other end to said sheave, said wall having an opening therein through which said element passes, a coil spring lying in a portion of said groove 50 and connected at one end to said block and at its other end to said sheave, and means whereby when said block is rotated to pull a rod or wire through reducing means said sheave is caused to rotate with said block, said spring 55 being adapted after the rod or wire has been wrapped on said wall sufficiently to cause the pulling force to be transmitted through the rod or wire itself to rotate the sheave relatively to the block to draw in the grip device and take up the slack in the rod or wire, substantially as described.

2. In a wire drawing mechanism, a drawing block, a drive shaft for the block, a sheave member in the drawing block concentric thereto and relatively rotatable therein, a

yieldable connection between the sheave member and the block adapted to be put under tension by movement of the sheave relatively to the block member in a direction opposite the normal direction of rotation of the block in drawing wire, releasable means for holding the sheave member against rotation after the sheave has been rotated to place the yieldable connection under tension, and cooperating abutments on the block and the sheave member for positively transmitting motion from the block to the sheave member after there has been a predetermined relative movement between the block and the sheave member, said abutments being so positioned as to be out of contact in the starting position of the drum, whereby the spring is placed under further tension at the beginning of the drawing operation.

3. In a wire drawing mechanism, a drive shaft, a drawing block fixed thereon, a grip device, a member rotatable within said block, a yieldable connection between said member and said block tending to rotate the member in the same direction that the block is rotated in drawing the metal, a flexible connector between the grip device and said member, cooperating stops on said block and said member for effecting rotation of the member with the block, said stops being normally out of engagement when the block is stationary whereby a relative movement between the block and the said member may occur upon initial rotation of the block, and a self-releasing latch for limiting rotation of said member by said yielding means in the direction of rotation of the block to prevent rotation of the member relatively to the block in the direction of rotation of the block until said stops are in contact with each other.

4. In a wire drawing mechanism, a drawing block, a drive shaft for the block, a relatively movable member associated with the block, a resilient connection between the block and the member, a pawl on such member, a ratchet disk on the drive shaft having a notch therein for cooperation with the pawl, said pawl and ratchet being provided for releasably holding the resilient connection under tension when there has been a predetermined relative movement between the member and the block, cooperating driving means on the member and the block which are normally out of contact when the block is stationary and when the pawl is engaged in the notch of the ratchet disk whereby a relative movement of the block with respect to said member will occur when the block is initially rotated, and a gripping device flexibly connected to the relatively movable member.

5. In a wire drawing mechanism, a drawing block, a drive shaft for the block, a relatively movable member associated with the block, a resilient connection between the block and the member, a pawl on such mem-

ber, a ratchet disk on the drive shaft having a notch therein for cooperation with the pawl, said pawl and ratchet being provided for releasably holding the resilient connection under tension when there has been a predetermined relative movement between the member and the block, cooperating driving means on the member and the block which are normally out of contact when the block is stationary and when the pawl is engaged in the notch of the ratchet disk whereby a relative movement of the block with respect to said member will occur when the block is initially rotated, and a gripping device flexibly connected to the relatively movable member, said pawl being adapted to be disengaged from the notch by such relative movement of the block with respect to said member, the relatively movable member being concentrically rotatable in the block.

6. Apparatus for drawing wire comprising a block, a chain having a wire gripping chuck, a retracting means for the chain within the block, and to which the chain is attached, a block engaging portion on the retracting means, said retracting means being movable from a position where the chain is retracted to a position where the chain is fully extended, means on the block for cooperation with the block engaging portion of the retracting means when the chain is fully extended, and a holding member for releasably retaining the retracting means between the two positions.

35 7. Apparatus for drawing wire comprising a block, a chain having a wire gripping chuck, a retracting means for the chain within the block and to which the chain is attached, a block engaging portion on the retracting means, said retracting means being movable from a position where the chain is retracted to a position where the chain is fully extended, a spring for yieldably opposing the movement of the retracting means 40 to the fully extended position, and for returning the retracting means to a position where the chain is retracted, means on the block adapted to engage the block engaging portion of the retracting means when the chain is fully extended, whereby motion is transmitted from the block to the retracting means, and a holding mechanism for retaining the retracting means between the said two positions.

55 8. Apparatus for drawing wire comprising a block, a chain having a wire gripping chuck, a retracting means for the chain within the block and to which the chain is attached, a block engaging portion on the retracting means, said retracting means being movable from a position where the chain is retracted to a position where the chain is fully extended, a spring for yieldably opposing the movement of the retracting means 60 to the fully extended position, and for re-

turning the retracting means to a position where the chain is retracted, means on the block adapted to engage the block engaging portion of the retracting means when the chain is fully extended, whereby motion is transmitted from the block to the retracting means, and a holding mechanism for retaining the retracting means between the said two positions, said holding means being self-releasing upon movement of the retracting means to the position where the chain is fully extended.

9. Apparatus for drawing wire comprising a block, a chain having a wire gripping chuck, a retracting means for the chain comprising a member rotatably mounted in the block and to which the chain is connected, a stop engaging means on said member, a pair of spaced stops on the block for cooperation with the stop engaging means on said member, said member being rotatable between the stops from a position where the chain is retracted to a position where the chain is fully extended, a spring for yieldably opposing within the limits of the stops any rotation of the member from a position where the chain is retracted and for returning the member to a position where the chain is retracted, and a holding mechanism for retaining the said member in a position where the stop engaging means is out of contact with both stops.

In testimony whereof I have hereunto set my hand.
